UNITED STATES PATENT OFFICE.

JAMES JOHN DENNY, OF SCHUMACHER, ONTARIO, CANADA.

CRUSHING MACHINE.

Application filed October 1, 1926. Serial No. 128,988.

The principal object of the invention is to produce a crushing machine for rock or other materials which will reduce rock of either large or small size to a desired fineness in a single operation, thus reducing the cost to the minimum.

A further object is to produce a machine which will not become choked or clogged with the finely crushed stone thus enabling the machine being maintained in continuous operation.

The principal feature of the invention consists in the novel arrangement of a pair of convergently disposed travelling walls 15 formed of a continuous series of crushing plates, the rock or material to be crushed being fed between the travelling walls and being carried thereby and crushed continuously as it advances toward the converging 20 end, emerging therefrom in the desired state of fineness.

A further feature consists in providing the travelling walls with a series of guiding rollers which engage the back surface of the 25 crushing plates of which the walls are formed, the rollers rigidly opposing the outward thrust caused by the rocks as they are being crushed between the walls.

In the drawings Figure 1 is a side elevational view of a machine constructed in accordance with this invention.

Figure 2 is a longitudinal vertical view of the machine.

Figure 3 is a plan view of the machine.

Figure 4 is a detail illustrating a modified form of crusher plates.

The present invention has been devised particularly for use in mining operations where it is necessary to reduce large quantities of metal bearing rock to a fine state of pulverization in order to facilitate the subsequent treatment of the rock for the removal of its metal content.

Various kinds of machines have been employed for this purpose principal among them being the common jaw type crusher and stamp mills and rolls. Such machines however have a very limited capacity and do not reduce the rock to a sufficiently fine state in one operation.

With such machines it is found necessary to employ a great number of machines in order to maintain production, directing the rock through various stages of disintegration by passing it from one machine to the other. Such arrangements require consid-

erable power in order to maintain the machines in operation.

The present invention aims to overcome these undesirable features by reducing to a single operation the crushing of the rock, irrespective of its size and reducing the same to an extremely fine state of pulverization.

In carrying the present invention into effect a pair of frame members 1 are provided which are spaced apart. Supported in suitable bearings 2 at one end of the frames and extending transversely therebetween is a shaft 3. Similarly disposed at the other end of the machine but preferably at a slightly higher level is the shaft 4 which is rotatably supported in the bearings 5 carried by the frames 1.

Rigidly mounted on each of the shafts 3 and 4 are a pair of heavy sprocket wheels 6 and 7 respectively, the sprockets being mounted on the shafts adjacent to the supporting bearings and in alignment with each other.

Heavy endless chain members 8 extending around each pair of aligned sprocket wheels 6 and 7 and secured to these chain members and extending transversely therebetween are a series of heavy crushing plates 9, arranged one adjacent the other. The plates 9 are made fairly narrow in order that they will readily follow around the sprockets as the chains pass thereover and are adapted to present a continuous travelling crushing surface extending between the aligned sprocket members, which surface, by reason of the difference in levels of the shafts 3 and 4 will form an incline.

Rollers 10 are mounted on the shafts 3 and 4 and serve to support the crushing plates as they pass around the sprockets.

A series of rollers 11 carried in blocks 12 mounted in the frame members 1 extend transversely below the upper travelling section of the crushing members, the rollers engaging the under surface of the crushing plates 9 and rigidly supporting the same against outward pressure and maintaining the members in a common inclined plane. The rollers 11 are spaced closely together 100 and extend well up to the rollers 10 on the shafts 3 and 4 in order to offer a continuous support to the crushing plates 9.

Extending transversely of the frame 1 and spaced above the shafts 3 and 4 are the 110 shafts 13 and 14 respectively. These shafts are preferably arranged in the same hori-

zontal plane and the shaft 13 is preferably set a little to the rear of the shaft 3. The shafts 13 and 14 are rotatably mounted in bearing blocks 15 vertically slideable in the 5 guideways 16 of the frame. Heavy coiled compression springs 17 are arranged above the blocks 15 and exert a heavy downward pressure thereon to normally hold the blocks to their downward limit.

10 Sprocket wheels 18 and 19 similar to the sprockets 6 and 7 are mounted on the shafts 13 and 14 respectively, and around these extend heavy endless chains 20 similar to the chains 8 on the sprockets 6 and 7.

15 Crushing plates 21 extend between the chains 20 and are suitably secured thereto in the same manner as the plates 9 on the lower travelling section and since the shafts 13 and 14 are each arranged in the same horizontal plane, the plates 21 converge toward the plates 9 until at the discharge end of the machine the upper and lower plates are brought into pressure contact, thus providing a converging crushing passage which presents a continuous crushing surface. Rollers 22 are mounted on the shafts 13 and 14 between the sprockets and serve to support the crusher plates as they pass around the sprockets.

20 A series of rollers 23 mounted in the blocks 24 carried in the frame 1 extend transversely above the lower side of the upper travelling section of the crushing members 21 and rigidly support same against the outward pressure thereon.

25 In the operation of the device the upper and lower sprockets are rotated in opposite directions, the shafts being connected with any suitable power device, and the sprockets 40 are rotated at any suitable speed.

30 The rotating of the sprockets causes the opposed sections of crushing members 9 and 21 to travel in the direction of the convergent end. Consequently rock placed on the lower section of crushers 9 will be carried inwardly and progressively crushed. This crushing process will continue to reduce the rock progressively to a condition of finer pulverization as the rock is carried toward 45 the discharge end, the crushing continuing until the pulverized rock passes out from between the crushing sections.

35 The crushing strain will all be taken up by the rollers 11 and 23 engaging the outward surfaces of the crushing plates and friction will be reduced to a minimum and since the crushing plates can not yield outwardly by reason of the support of the rollers, a very positive crushing force will be 50 applied to the rock ensuring its complete reduction to the desired state of fineness in which state it passes out from between the final rollers 10 and 22 at the rear of the machine.

In the event of an exceptionally large 65 piece of rock being fed into the machine, the roller 22 on the upper shaft 13 will yield sufficiently against the heavy springs 16 to permit it to pass into the machine, thus preventing damage to the sprockets or 70 to the crusher plates at a point where they are not supported by rollers.

75 In the modified form of crusher plate illustrated in Figure 4, the underside of the plates 25 are provided with heavy teeth 26. These teeth engage the teeth on the sprockets which carry the same forward. Suitable link connections 27 pivotally connect the plates together and serve to space the 80 members.

85 The lower set of crushers may, if found desirable, be operated at a speed slightly in excess of the upper set of crushers and in this way a spreading influence will be imparted to the rock as it is being crushed, thus effecting its distribution and preventing the same from forming into packs.

90 A machine such as described will have an exceptionally large capacity, will not become choked and will require a minimum amount of power to operate it.

95 Such a machine may be employed with equal success for the purpose of producing crushed stone for building or other purposes, the size of grain of the crushed stone being governed by the distance between the crusher plates, which distance may be varied by suitable means for adjusting their relative positions. If desired, the shaft 14 having the roller 22 mounted thereon may be 100 mounted for fixed vertical adjustments so that by setting the same up or down relative to the lower roller 10, the final crushing of the stone may be readily governed.

105 What I claim as my invention is:—

110 A crushing machine, comprising a rigid frame, paired shafts journaled parallelly in said frame and having sprockets mounted thereon at each end, cylindrical rollers mounted on said shafts and extending between said sprockets, a plurality of crusher plates having their back surfaces each formed in a flat plane, said crusher plates being linked together to form a pair of endless crusher belts extending around said rollers and driven at either side by said sprockets and arranged to present convergent moving surfaces between said rollers, said rollers engaging the plane back surfaces of said crusher plates to support same throughout 115 their length as the plates are advanced thereover, and cylindrical rollers journaled in a fixed position in the frame and engaging the rear plane surfaces of said crusher plates of the convergent moving portions of 120 said crusher belts as they pass from one of said rollers to the other.

125 JAMES JOHN DENNY.
